UNITED STATES PATENT OFFICE.

HEINRICH ALDER AND JOHANN MEISTER, OF ZURICH, SWITZERLAND.

CATEMENIAL APPLIANCE.

Application filed September 26, 1924, Serial No. 740,089, and in Belgium July 2, 1924.

- The invention relates to a new and improved catamenial appliance and more particularly to sanitary towels for wear by women during the menstrual period.
- 5 The object of the invention is to provide an improved appliance which is easy to be cleaned and comfortable in wearing.
- The new appliance consists of a pad of absorbent material, such as cotton wool arranged in a wrapper of waterproof material 10 perforated in a suitable manner and closed by buttons of particular construction. The appliance is provided with buttons and button holes by means of which the appliance 15 may be attached to a waistband.
- In the drawing one form of construction is shown by way of an example.
- Figs. 1 and 2 are two side views of the appliance.
- 20 Fig. 3 is a cross-section.
- The appliance shown comprises a sheet 1 of waterproofed material for instance an india-rubber sheet which forms a wrapper for a pad 4 of absorbent material such as for instance cotton wool, lint, sponge or other fibrous material. The sheet 1 is provided along its edge with button holes and at the 25 opposite edge two buttons 2 having each a flap 3 which facilitate the unbuttoning of the wrapper. The sheet 1 is perforated at 30 5. At the small end the sheet 1 is provided with buttons 6 and buttonholes 7 by means of which the sheet 1 may be attached to straps. The wrapper may be easily opened as the buttons 2 may be firmly held by the flaps 3, 35 the sheet 1 may be flattened and the pad 4 can be removed.
- The appliance once open is easily cleaned, the sheet 1 may be washed.
- What we wish to secure by U. S. Letters 40 Patent is:
- A catamenial appliance, comprising a sheet of water proof material of uniform thickness designed to form an envelope for an absorbent pad and formed with a 45 series of comparatively small perforations throughout the full width and a portion of the length of the face portion of such envelope, the longitudinal edges of the sheet being in lapped relation and having complementary fastening means, and strap attaching means arranged at the end of the envelope beyond the pad.
- In witness whereof we affix our signatures.
- ALDER, HEINR.
J. MEISTER.
